STYLED MODEL POWER SHOVEL

Eugene T. Daniel, Walnut, Calif., assignor to
Monogram Models, Inc., Morton Grove, Ill.

Filed Aug. 31, 1972, Ser. No. 285,413

Term of patent 14 years

Int. Cl. D21—01

U.S. Cl. D34—15 T

FIG. 1

FIG. 2

FIG. 3

FIG. 4

FIG. 5

FIG. 6

FIG. 1 is a left-side elevational view of the stylized model power shovel showing my new design;
FIG. 2 is a top plan view thereof;
FIG. 3 is a front elevational view thereof;
FIG. 4 is a rear elevational view thereof;
FIG. 5 is a right-side elevational view thereof; and
FIG. 6 is a bottom plan view thereof.

I claim:
The ornamental design for a stylized model power shovel, as shown.
